Application September 18, 1947, Serial No. 774,875

27 Claims. (Cl. 3—1.2)

1

My invention relates to improvements in artificial limbs, and more particularly to improved knee-brake mechanisms and controls therefor.

In many artificial legs the upper limb member and the lower limb member are pivotally connected by a knee-joint. Such a knee-joint acts as a hinge to permit the legs to bend or flex, and to extend or straighten. In artificial legs which are designed to simulate the action of the natural legs they replace, it is highly desirable to employ a knee-brake, or knee-lock, mechanism which prevents flexion of the knee-joint under a wide variety of conditions without, however, interfering with the extension of the knee-joint. Such a knee-brake mechanism serves to protect its user from many falls caused by involuntary knee-buckling; but still provides him with a great deal of freedom of movement.

One of the principal objects of my invention is to provide an artificial leg with an improved knee-brake mechanism which serves to prevent involuntary buckling of the knee-joint under a wide variety of conditions.

Another object of my invention is to provide a knee-brake mechanism which responds to involuntary flexion of the ball-joint of the foot of the artificial leg. A more particular object is to provide an artificial leg having a ball-joint and employing a toe control unit, to actuate a knee-brake mechanism with means for adjusting the point of inception of operation of the control unit according to the degree of flexion of the ball-joint. A still more particular object is to provide an artificial leg employing a toe control unit for actuating a knee-brake mechanism with means for adjusting the point of inception of operation of the control unit by means of an adjustment device located on the upper leg member and while the artificial leg is in use. A still further object is to provide a toe control unit which automatically seats itself in a position corresponding to a minimum degree of ball-joint flexion in the event of failure of the means for adjusting the point of inception of operation. And still a further object is to provide an artificial leg with a toe control unit which is hydraulically adjusted from a position on an upper leg member for setting the point of inception of operation. And a still further object is to provide an adjustment device by means of which the point of inception of operation may be adjustably set at any one of a series of selected positions while the artificial leg is in use.

Another object of my invention is to provide an artificial leg with a knee-brake mechanism

2

which responds to pressure on the heel. A more particular object is to provide an artificial leg employing a heel control unit for operating a knee-brake mechanism with means for adjusting the point of inception of operation thereof according to the amount of pressure applied to the heel.

Another object of my invention is to provide an artificial leg with a knee-brake mechanism which responds either to ball-joint flexion or to heel pressure. A further object is to provide an artificial leg employing a hydraulic knee-brake mechanism with mechanical control units respectively responsive to actuate the knee-brake mechanism in accordance with ball-joint flexion and heel pressure. A still further object is to provide such an artificial leg with hydraulic control units which are respectively responsive to ball-joint flexion and heel pressure. And still a further object is to provide such an artificial leg with electrical control units which are respectively responsive to ball-joint flexion and heel pressure.

Another object of my invention is to provide an artificial leg with an upper leg member and a knee-brake mechanism which are adapted for use on a leg which is amputated below the knee.

Another object of my invention is to provide an artificial leg with a knee-brake mechanism which can be voluntarily released during operation in order to permit knee flexion. A still further object is to provide an artificial leg employing a knee-brake mechanism with a control device which can be voluntarily operated to render the knee-brake mechanism operative to lock the knee against flexion, and which then effectively releases the braking mechanism to any selected degree so as to control the rate of knee flexion as desired. And still a further object is to provide such a control device which is manually operative from the hip position of the upper leg member while the artificial leg is in use.

Another object of my invention is to provide an artificial foot with a control unit which is adapted to actuate a knee-brake mechanism. A further object is to provide an articulated artificial foot with a control unit which is responsive to ball-joint flexion. A still further object of my invention is to provide an artificial foot employing a toe control unit with means for adjusting the point of inception of operation thereof according to the degree of ball-joint flexion.

Another object of my invention is to provide an artificial foot with a control unit which is responsive to heel pressure. A still further object

is to provide an artificial foot employing a heel control unit with means for adjusting the point of inception of operation thereof according to the amount of pressure applied to the heel.

Another object of my invention is to provide an articulated artificial foot employing a ball-joint control unit and a heel control unit with common means for communicating a control force to a remote point.

Another object of my invention is to provide an articulated artificial foot with an improved ball-joint that is rugged and not subject to side sway.

Another object of my invention is to provide an improved knee-brake mechanism employing a brake-piston operating in a cylinder, and a check valve mechanism arranged in a passageway communicating with spaces within the cylinder on opposite sides of the piston. A further object of my invention is to provide a hydraulic knee-brake mechanism with a check valve mechanism which employs a valve head which floats resiliently therein, and which is movable between a withdrawn position in which liquid is free to flow in either direction therethrough and an operative position in which liquid is free to flow therethrough in only one direction. A further object is to provide a hydraulic knee-brake mechanism employing a brake-piston operating in a cylinder with two passageways each communicating with the spaces in the cylinder on opposite sides of the piston, and a check valve in one of the passageways which may be rendered operative to limit the flow therethrough to one direction and a throttle valve in the other passageway which may be adjusted to control the rate of flow therethrough in the opposite direction in by-passing relationship to the check valve. A still further object of my invention is to provide such a hydraulic knee-brake mechanism with common means for sequentially rendering the check valve operative and for adjusting the opening of the throttle valve.

There are many other objects of my invention which together with the foregoing objects and there are many advantages of my invention will be readily apparent from a consideration of the several embodiments thereof which are illustrated in the accompanying drawings and described below. Various features of these embodiments of the invention operate on mechanical, hydraulic, and electrical principles. While the various embodiments of the invention operating on such principles are herein illustrated and described in detail, it is to be understood that many forms of the invention, some of which might even incorporate detailed improvements to be discovered in the future, will occur to those skilled in the art without departing from the main principles underlying my invention. It is, therefore, to be understood that my invention is not to be limited in any of its features to the details of the embodiments illustrated and described herein, but that reference is to be made to the appended claims for a determination of the limits of my invention.

I. General construction of artificial leg

An artificial leg of the type to which my invention is particularly applicable is illustrated in Figs. 1, 2, 3, 6 and 8. This artificial leg is completely articulated and comprises a lower limb or leg member 30 pivotally attached to an upper limb or leg member 32 by means of a knee joint 34 and also comprises a foot member 36 pivotally attached to the lower leg member 30 by means of an ankle joint 38. The foot member 36 itself comprises a main foot section 40 and a toe section 42 pivotally attached thereto by means of a ball joint 44. The knee joint 34, the ankle joint 38, and the ball joint 44 are designed to pivot about substantially horizontal transverse axes. The upper leg member 32 is in the form of a socket which is adapted to fit over the stump of an above-the-knee amputated leg. The upper leg member 32 may be firmly secured in place on the amputated leg by any suitable means such as a belt or harness (not shown). If desired to adapt the artificial leg to a below-the-knee amputated leg, a rearwardly protruding pocket 46 as shown in Fig. 1a, may be provided at the lower rear portion of the upper leg member 32. In any event, a suitably cushioned liner 48 that fits the amputated leg snugly is used to support the amputated leg and hold its lowermost extremity spaced above the bottom open end 50 (see Fig. 6) of the upper leg member 32.

The knee joint includes a pair of upper hinge straps 52 suitably secured to the outer wall of the upper leg member 32 and also a pair of forked lower hinge straps 54 likewise suitably secured to the outer surface of the lower leg member 30. As shown in Figs. 6 and 10, the adjacent ends of the hinge straps on opposite sides of the knee are secured together by machine screws 56 and are arranged to rotate on roller bearings 60 to permit free pivotal movement at the knee joint. The straps 52 and 54 are provided with front stops 62 which abut when the upper and lower leg members 30 and 32 are extended into their aligned or straight position. They are also provided with rear stops 64 so as to limit the flexion of the knee joint to an angle of about 50°.

The lower leg member 30 is of hollow tubular construction shaped in the form of a natural lower leg, in order to provide a cavity in which the main working parts of a knee brake mechanism may be mounted as hereinafter explained. A shank piece 66 is fitted securely within the shin portion at the lower end of the lower leg member 30 and is provided with a pair of depending bearings 68 in which an ankle axle 70 is supported as shown in Figs. 3 and 8.

The main foot section 40 is provided with a recess 72 having side walls 74 which enclose the bearings 68 and the ankle axle 70. A supporting bracket 76 is mounted in the bottom of this recess and is provided with two semi-circular weight-bearing yokes 78 upon which the ankle axle rests. The eye 79 of a hollow eye-bolt 80, locked by means of a nut 82 to the main foot section 40, encloses the ankle axle 70 and serves to secure the lower leg member 30 and the foot member 36 together and to form a pivot at the ankle joint 38. Front and rear ankle bumpers 84 and 86 composed of resilient material, such as rubber, are firmly held in place between the lower wall 88 of the shank piece 66 and the base 90 of

the recess 72. The bumpers 84 and 86 are normally under slight compression and serve to restore the ankle joint 38 to its normal configuration when flexed rearwardly therefrom by stepping down on the heel portion 92 of the foot member 36 or when flexed forward therefrom by stepping down on the ball joint 44 or the toe section 42 of the foot member.

The ball joint 44 is formed by means of a flexible plate 94 and an overload bumper 96 attached thereto between adjacent faces of the main foot section 40 and the toe section 42. A resilient sole piece 98 underlies the bottom of the foot member 36 from the toe 100 to the arch 102. Likewise, a resilient heel piece 104 is secured to the lower side of the heel portion 92. The plate 94, the overload bumper 96, the sole piece 98, and the heel piece 104 may be formed from any suitable resilient material such as a rubber composition. It is to be noted that when the user of the artificial leg steps down on the toe section 42 or shifts his weight from the heel portion 92 to the toe section 42, the ball joint 44 flexes.

According to my invention, an improved knee brake mechanism is provided which locks the knee joint against any further flexion whenever the ball joint flexes more than a predetermined amount, and also locks the knee joint against further flexion whenever upward pressure exceeding a predetermined amount is applied to the heel portion. Preferably, the knee brake mechanism comprises a brake device which includes a pair of cooperating brake members respectively connected to the upper and lower leg members 30 and 32 and a toe control unit and a heel control unit which respond to predetermined action of the foot member to render the brake device operative to resist further flexion of the knee joint without, however, interfering with extension of the knee joint.

II. Hydraulic brake unit

A knee brake mechanism of the type which I prefer to employ in my invention comprises a hydraulic brake unit 110 which is located within the lower leg member 30 as indicated in Figs. 1 and 6. The brake unit 110 includes a body member 112 pivotally attached to the lower end of a pair of downwardly depending support brackets 114 firmly secured at their upper ends to the lower hinge straps 54. As illustrated in detail in Fig. 7, this body member 112 comprises a main elongated cylinder 116 closed at its ends by means of upper and lower threaded plugs 118 and 120. A double-acting piston 122 is slidably arranged within the cylinder 116 and is rigidly secured to a lower piston rod 124 which extends through the lower plug 120 and an upper piston rod 126 which extends through the upper plug 118.

The lower plug 120 is provided with a downwardly projecting nipple or plug extension 128 which is threaded at its end. A bearing member 130 is loosely held on the plug extension 128 by means of a nut 132 and is provided with two oppositely extending pins 134 which are seated in needle bearings 136 at the lower ends of the brackets 114.

As shown in Figs. 1 and 6, the upper piston rod 126 is attached by means of a loose fitting bolt and clevis 138 to a downwardly extending arm 140 at the bottom of a knee yoke 142 which is pivotally attached to downwardly inclined, rearwardly extending arms 144 on the upper hinge straps 52. These arms 144 preferably extend inwardly through side openings 146 in the sides of

the upper leg member 32, the yoke 142 being held within the upper leg member and extending downwardly through the bottom opening 50 therein. The use of such a yoke is particularly convenient when adapting the artificial leg to a below-the-knee amputated leg as it provides a space within which the knee is easily supported. The bolt and clevis 138 pivot about a forwardly extending axis so as to provide for small transverse sway between the upper and lower leg members 30 and 32 without bending the hydraulic brake unit 110.

The spaces 148 and 150 above and below the piston 122 communicate by means of upper and lower ports 152 and 154 respectively with an internal passage 156 which passes through a check valve 158, as shown in Fig. 7. It will be noted that the inner ends of the plugs 118 and 120 are chamfered in order to provide free access of the ports 152 and 154 to the spaces 148 and 150 on opposite sides of the piston 122.

The check valve 158 includes a body section 160 formed integrally with the body member 112 and includes a cylindrical chamber 162 which forms part of the passage 156 and thus communicates through the upper port 152 with the upper space 148 and through the lower port 154 with the lower space 150. A valve seat 164 is formed in the chamber 162 by means of a ring 166 which is press-fit therein. A head 168 of a valve 169 is arranged in the lower portion of the chamber 162 in working relationship with the valve seat 164. The valve 169 is provided with a downwardly directed extension 170 which is slidably arranged in a bore 172 which passes through the body section 160 coaxially with the chamber 162 and is piloted thereby to form a firm seal between the valve head 168 and the entire periphery of the valve seat 164 when the valve 169 is in its uppermost position. An operating member 174 which serves, in effect, as a valve rod is arranged in a counterbore 176 at the lower end of the bore 172.

The valve 169 is recessed at its upper and lower ends in order to receive compression springs 177 and 178 between which it is floated. The upper end of the upper compression spring 177 fits within a bore 179 in a threaded plug 180 which closes the upper end of the check valve chamber 162 and the lower end of this spring fits in the recess 182 at the upper end of the valve head 168. The lower end of the lower compression spring 178 fits within a tubular portion 184 of the operating member 174 which is slidably arranged in the lower end of the bore 172 and the upper end of this spring fits in the recess 186 at the bottom of the valve extension 170. The operating member 174 is provided with a flange 188 which slides in the counterbore 176 between a shoulder 189 at the inner end thereof and a stop ring 190 which is clamped in an annular groove 191 within the counterbore. The relative strengths of the two compression springs 177 and 178 are so chosen that the valve head 168 remains in a retracted or withdrawn position from the valve seat 164 when the operating member 174 is in its lowermost position with the flange 188 against the stop ring 190, and the valve head 168 operatively engages the valve seat 164 to act as a check valve when the operating member 174 is in its uppermost position with the flange 188 engaging the shoulder 189. The threaded plug 180 is preferably provided with a square head 192 by means of which the plug may be adjusted inwardly and outwardly of the check valve body section 160. This adjustment serves to vary the setting of the re-

tracted position of the valve head 168, so that the rate at which fluid may flow downwardly through the check valve 158 is varied. The resultant variable throttling or restriction of flow permits adjustment of the rate of knee joint extension, thereby eliminating the need for a friction element in the knee joint.

The spaces in the brake cylinder 116, the check valve chamber 162, and the intercommunicating passages therebetween are substantially filled with a liquid, preferably an oil having a low temperature coefficient of expansion. Suitable packing and seals are provided in all the hydraulic devices to prevent seepage of oil from such spaces or the leakage of air thereinto. In addition, an O-ring 193 is arranged in an annular groove 194 in the piston to prevent leakage of oil past the piston between the spaces 148 and 150 on opposite sides thereof. A small amount of air is left therein to accommodate volumetric changes due to movement of the valve 169 into and out of the chamber 162.

When the check valve 158 is inoperative, that is, when the valve head 168 is withdrawn from the valve seat 164, the liquid is free to be pumped by the piston 122 in either direction past the check valve as the knee joint 34 is flexed and straightened. But when the check valve 158 is operative, that is, when the valve head 168 is pressed against the valve seat 164, the flow of liquid in an upward direction through the check valve is blocked but liquid can flow therethrough in a downward direction. Thus, when the check valve 158 is operative downward, movement of the piston 122 within the cylinder 116 corresponding to flexion of the knee joint 34 is prevented. The additional upward pressure of the valve head 168 resulting from flexion serves to seat the valve head more firmly on the valve seat 164. However, when the check valve 158 is operative, it does not interfere with upward movement of the piston 122 in the cylinder 116 corresponding to extension of the knee joint 34.

III. Mechanical control units

According to my invention the check valve is rendered operative in response to predetermined movement of a part of the artificial leg in order to lock the knee joint against further flexion, whenever that predetermined movement occurs. A slave device is provided on the lower portion of the body member in order to force the operating member upward whenever this predetermined movement occurs. In the form of the invention illustrated in Figs. 1 to 10 inclusive, the actuation of the hydraulic brake unit is accomplished entirely mechanically, that is, the toe control unit, the heel control unit, and the slave device are all of mechanical construction.

As shown in detail in Fig. 7, the slave device 200 of this artificial leg includes an actuator rod 202 which is slidably arranged in a pilot sleeve 204 in a solid branch arm 206 of an apertured cup-like supporting member 208 which is held on the nipple 128 directly above the bearing member 130. A slot (not shown) on one side of the supporting member 208 fits snugly over the protruding portion 210 of the body member 212 in which the external passage 156 is formed, in order to maintain the actuator rod 202 registered in vertical alignment with the valve rod 174.

The control unit 212 comprises two cooperating actuating members 214 and 216 mounted respectively on the toe section 42 and the main

foot section 40, as illustrated particularly in Fig. 3. The actuating members 212 and 214 are arranged to cooperate in the actuation of the hydraulic brake unit 110 when the ball joint 44 is flexed more than a predetermined amount. More particularly, in the embodiment of the toe control unit 212 illustrated in detail in Fig. 3, one of the actuating members comprises a toe bumper 214 which is adjustably positioned on the rear face 218 of the toe section 42. This member 214 comprises a narrow rubber block 219 having a width of about $\frac{1}{8}$ of an inch, covered at its rear and front ends by means of flexible metal cover segments 220 and 222. The entire bumper 214 is arranged to be compressed and to expand longitudinally in a narrow vertical groove 223 cut in the upper side 224 and the rear face 218 of the toe section 42. The adjustment of the position of the bumper 214 is accomplished by means of a screw 225 which is attached to the front cover segment 222 and which passes through a bore 226 extending to the toe 100. The screw 225 engages a threaded insert 228 which fits within a transverse recess 230 in the upper side 224 of the toe section 42. With this arrangement, to adjust the toe bumper 214 in position backward or forward in the toe section 42, it is only necessary to insert a screw driver into the forward end of the bore 226 and turn the screw 225 in the desired direction.

The other actuating member 216 of the toe control unit 212 comprises a toe rod 231 which is arranged to be moved forward and backward in a longitudinal bore 232 which extends from the front face 234 of the main foot section 40 to a point adjacent the heel portion 92. An elongated tubular cap 236 is press-fit over the forward end of the toe rod 231 and is arranged to slide within a pilot sleeve 238 which is press-fit within the front end of the bore 232. The sleeve 238 is flared inwardly at its inner end 239 and a compression spring 240 is arranged within the sleeve between the cap 236 and this flaring end, in order to urge the toe rod 231 forwardly into a position opposite the bumper 214. The rear end of the toe rod 231 slides within a guide 242 adjacent the heel, this guide being provided with a vertical slot 244 in which the rear end 245 of the toe rod may be moved vertically for purposes to be explained hereinafter. The guide 242 is held firmly in place by means of a bolt 246 which also serves to hold the supporting bracket 16 of the ankle joint 38 in place.

A vertical push rod 248 is arranged to slide vertically in a bore 249 passing longitudinally through the eye-bolt 80 and transversely through the ankle axle 70. The push rod 248 is provided with a head 250 at its lowermost end against which a compression spring 252 works to maintain the push rod in contact with the upper side of the toe rod 231. An extended upwardly protruding cam 254 is formed in the toe rod 231 at a point slightly forward of the push rod 248 and the sides of the rear end 245 of the toe rod 231 are flattened so that when it is forced rearwardly by the toe bumper 214, the cam 254 forces the push rod 248 upwardly.

A cup-shaped socket 256 screwed into the upper end of the main push rod 248 serves to support the lowermost end of an auxiliary push rod 258 which is pivotally attached to the lowermost end of the actuator rod 202 by means of a loose-fitting tubular connector 260 and a cotter pin 262, as indicated in Fig. 5. The lowermost end

of the auxiliary push rod 258 is capped by a rounded tip-piece 264 which fits closely but not tightly within the socket 256. A compression spring 266 arranged between the connector 260 and the pilot sleeve 204 serves to maintain the tip-piece 264 in positive engagement with the socket 256.

With this arrangement, when the ball joint 44 is flexed more than a predetermined amount, the bumper 214 pushes the toe rod 231 rearwardly against the force of the compression spring 240. As a result the cam 254 forces the main push rod 248 and the auxiliary push rod 258 upward against the force of the springs 252 and 266, thereby forcing the actuator rod 202 into engagement with the valve rod 174, forcing the valve head 168 upward against the valve seat 164, thereby rendering the check valve 158 operative. When the ball joint 44 is extended or straightened, the compression spring 240 forces the toe rod 231 forwardly, withdrawing the cam 254 from the main push rod 248 so that the springs 252 and 266 force the main push rod 248 and the auxiliary push rod 258 downwardly, thus causing the valve rod 174 to be drawn downwardly withdrawing the valve head 168 from the valve seat 164, thereby rendering the check valve 158 inoperative.

The heel control unit 267 illustrated in Fig. 3 comprises a heel lever 268 which is pivotally attached at the arch portion 132 of the main foot section 40 at 270 for pivotal movement about a transverse horizontal axis. The heel lever 268 extends rearwardly from the pivot point and terminates in a downwardly projecting finger 272 substantially flush with the bottom surface of the resilient heel piece 104 so that it may be forced upwardly when an upward pressure exceeding a predetermined amount is applied to the heel portion 92. An upwardly projected finger 274 is formed in the heel lever 268 intermediate its ends and directly beneath the head 250 of the main push rod 248 and in contact with the lower side of the toe rod 231.

With this arrangement when an upward pressure exceeding a predetermined amount is applied to the heel portion 92 as when the user of the artificial leg steps down on the heel portion, the main push rod 248 and the auxiliary push rod 258 are forced upwardly, thereby rendering the check valve 158 operative, and when the pressure on the heel portion is released, the main push rod and the auxiliary push rod are forced downwardly in the manner previously explained, thereby rendering the check valve inoperative. As the heel lever 268 is forced upward, the toe rod 231 bends and its rear end 245 slides upward in the slot 244 and when the heel lever is released, the toe rod straightens and its rear end returns to its former position in the bottom of the slot.

From the foregoing, it is readily seen that the check valve is rendered operative upon actuation of either the toe control unit or the heel control unit. In either event, the knee joint 34 is locked against further flexion in whatever position it then finds itself without, however, interfering with any extension thereof.

IV. Operation of artificial leg with mechanical control unit

Consider now the operation of this artificial leg commencing from a standing position, and assume by way of example that the artificial leg is the user's right leg and that his left leg is

natural. In the normal standing position the ball joint is straight and there is little, if any, pressure on the heel portion. In this condition, fluid is free to pass in either direction through the check valve, but since the leg is straight it is actually only prepared for flexion of the knee joint.

If, for any reason, while in the standing position, the user should commence to fall forward while the foot member is on the ground, both the knee joint and the ball joint commence to flex. With the knee brake mechanism of the present invention, however, as soon as the ball joint flexes more than a predetermined amount, the toe control unit renders the check valve operative, thus preventing upward flow of liquid therethrough and locking the knee joint against any further flexion. This locking of the knee joint prevents collapse of the artificial leg and breaks the user's fall. With his artificial leg in this condition, even though further flexion of the knee joint is blocked, the user may raise himself, causing the artificial leg to straighten, by virtue of the fact that the flow of fluid past the check valve in a direction corresponding to knee joint extension is permitted.

If, while in the standing position, the user starts to walk forward, commencing with his left foot, his weight is first shifted to his artificial leg and as he moves forward both the knee joint and the ball joint of the artificial leg flex. As before, when the ball joint is flexed more than a predetermined amount, the knee joint is locked against flexion, thus preventing the artificial leg from collapsing. While the knee joint is so locked, the user may continue the forward advance of his natural leg without danger of buckling of the artificial leg. When the left foot strikes the ground, the user's weight is shifted thereto and he raises his artificial leg, throwing it forward and straightening the knee as he does so by the inertial effect of the forward movement. As he places the artificial leg downward on the ground, he shifts his weight to the heel portion of the artificial leg, rendering the check valve operative and thus locking the knee joint against flexion. With his weight on the heel portion of his artificial leg, the user lifts his left leg and steps forward. As his body is carried forward, he shifts his weight from the heel portion and then to the toe portion. As his weight is so shifted, the knee joint is flexed slightly and then the ball joint flexed in the manner explained above and he is able to continue the alternating operation of the natural leg and the artificial leg, closely simulating walking with two natural legs.

While in the standing position, if desired, the user may shift his weight to the heel portion of the artificial foot member, thus locking the hydraulic unit against knee joint flexion, and step backward with his left leg.

In order to seat himself, the user of this artificial leg shifts the weight of the artificial leg to the ball joint without flexing the ball joint and he flexes his artificial knee joint as he lowers himself, carrying most of his weight on his left leg. In order to rise from a sitting to a standing position, the user, as a safety precaution, shifts his weight to the heel portion of his artificial leg and straightens the knee joint of the artificial leg as he uses his left leg in rising.

In order to climb stairs, the user shifts his weight to the heel portion or the toe section of his artificial leg, locking the knee joint against flexion while he advances the left foot, flexing

the natural leg. In this operation the artificial leg supports him while he carries himself forward to place the left foot on the next higher step. He then raises the foot of his artificial leg to this step by bringing it forward and straightening the natural leg at the same time. He then advances his left leg as before described and repeats the action as he progresses up the stairs.

To descend stairs, the artificial leg is periodically advanced to the next lower stair as the natural leg is flexed. The user's weight is then shifted to the heel portion of the artificial leg and the left foot is moved to the same stair. In this operation, as the artificial leg is lowered to the next forward stair, the weight of the user is supported by the left leg while this leg is flexed, and the artificial leg is then held straight by means of pressure applied to the heel portion of the artificial leg as the left leg is advanced.

V. Hydraulic control units

In the embodiment of my invention illustrated in Figs. 11 to 17 inclusive, a toe control unit, a heel control unit, and an intermediate or slave device of the hydraulic type are employed to actuate the hydraulic brake mechanism in response to predetermined ball joint flexion and a heel pressure. This embodiment of the invention also includes provision for adjusting the toe control unit during use to vary the point of inception of operation of the toe control unit according to the requirements of the user.

The slave device 280, which is substituted for the slave device 200 of Fig. 7, comprises a slave cylinder 282 formed unitary with the body member 112 of the hydraulic brake unit 110. Such a slave device 280 is illustrated in detail in Fig. 17. More particularly, the actuator rod 284 in this case is attached to a piston 286 which is slidably arranged within the slave cylinder 282. The piston 286 is normally forced downwardly into its lowermost position by means of a compression spring 281. The working chamber 288 within the slave cylinder 282 communicates with the toe control unit and the heel control unit by means of flexible tubing 289 having two branches 290 and 291 composed, for example, of a resilient thermoset plastic-derived material.

The toe control unit 292 comprises a compound cylinder structure 294, including an outer cylinder 295 firmly mounted on the main foot portion 36. An inner cylinder 298 is slidably arranged within the primary cylinder and a piston 300 connected to a toe rod 302 is slidably arranged within the inner cylinder. The inner cylinder 298 acts as a master cylinder with respect to the slave cylinder 282, as more fully explained hereinbelow. More particularly, as illustrated in Fig. 16, the outer cylinder 296 comprises a body member 304 which is closed at its lowermost end by a threaded cap 306 and the chamber 303 formed within this cylinder communicates by means of a passage 310 with a hydraulic control line or conduit 312. The inner cylinder 298 comprises a body member 314 having a cylindrical head 316 extending through the cap 306 and a tubular tailpiece 320 threadably secured to the opposite end of the body member 314 and extending through the other body member 304. The tailpiece 320 is connected to the lowermost end of the conduit branch 290 to provide communication between the chamber 321 in the master cylinder 298 and the chamber 288 in the slave cylinder 282. The head 316 and the tailpiece 320 are arranged to slide in the cap 306.

and the body member 304 in order to guide the inner cylinder 298 within the primary cylinder 296. A flange or collar 322 formed on the outer surface of the body 314 of the secondary cylinder 298 slidably engages the wall of the primary cylinder 296 and acts as a piston therein. A compression spring 324 arranged between the flange 322 and the cap 306 normally urges the inner cylinder 298 inwardly in the outer cylinder 296 against the pressure of any hydraulic fluid contained in the outer cylinder chamber 308.

The control line 312 leads upward through a hole 324 in the outer side of the lower leg member 30 to an adjustment device 326 which is mounted at the hip position on the upper leg member 32. The adjustment device 326 comprises a control cylinder 328 in which a control piston 330 may be adjustably positioned by means of a manually adjustable knob 332 connected thereto through a suitable linkage 334, as illustrated, for example, in Fig. 14. A stop mechanism including a ball 336 and spring 338 mounted on the housing 333 of the adjusting device 326 co-operate with recesses 340 on the inner side of the knob 332 to set the knob and hence the piston 330 in any desired position within its range of movement.

In operation, as the control piston 330 is moved downward in the control cylinder 328, fluid is forced into the outer cylinder chamber 308 through the control line 312, thus forcing the inner cylinder 298 toward the toe section 42 of the foot member 36. Conversely, as the control piston 330 is raised, the inner cylinder 298 is retracted into the primary cylinder 296, thus withdrawing it from the toe section 42. Movement of the inner cylinder 298 serves to adjust the point of inception of operation of the toe control unit 292.

In the control unit 292 the toe bumper comprises an arm 342 attached to one end of a torsion spring 344 arranged on a transverse rod 346 in the toe section 42, as illustrated in Fig. 13. The end of the spring 344 remote from the arm 342 presses against the toe rear face 343 and a detent 345 is mounted on the face 343 near the outer edge of the arm 342 to limit its rearward movement toward the toe rod 302.

The heel control unit 350 comprises a master cylinder 352 which is firmly attached to the base 88 of the shank piece 66 behind the ankle axle 70 and also a piston 354 slidably arranged therein to move upward in response to heel pressure. The conduit branch 291 is connected to the upper end of the cylinder 352 in order to provide communication with the chamber 353 therein. This piston is mounted upon the upper end of a rod 356 which carries at its lower end a guide head 360 adapted to slide within a tubular guide 360 mounted above the heel portion of the main foot section 40. A compression spring 362 is arranged within the guide 360 to urge the piston 354 upwards. A ring 355 press-fitted within the cylinder 352 limits the downward movement of the piston 354. The rod 356 and the guide 360 are arranged within a bore 364 which passes vertically through the heel piece 104, the heel portion 92 and the rear ankle bumper 86; and the guide 360 is arranged on the inner end of a screw 366 which may be adjusted vertically in the main foot section 40. A set screw 368 is provided for fixing the adjustment screw 366 in any desired position.

The chamber 288 in the slave cylinder 282, the chamber 321 in the master cylinder 298 of the

toe control unit 292, the chamber 353 in the master cylinder 352 of the heel control unit 350, and the interconnecting conduits 289, 290 and 291 are substantially filled with oil or other hydraulic fluid. It is to be understood, of course, that suitable seals and gaskets are employed to prevent leakage of oil out of or air into any of the hydraulic systems described herein.

With the hydraulic control system described, the check valve 158 (see Fig. 7) is rendered operative as before in response to predetermined ball joint flexion and heel pressure. In particular, when the ball joint 44 is flexed more than a predetermined amount, the bumper arm 342 engages the toe rod 302, forcing the piston 308 inwardly within the master cylinder 298, contracting the chamber 321 therein, thereby forcing fluid into the chamber 288 in the slave cylinder 282, expanding the latter chamber and raising the actuator rod 284 into engagement with the check valve rod 184, rendering the check valve mechanism 158 operative. In a similar manner, when pressure exceeding a predetermined amount is applied to the heel portion 92, the ankle joint 38 is flexed, forcing the piston 354 upwardly in the second master cylinder as indicated in Fig. 12a; and also forcing fluid into the slave cylinder 282 and rendering the check valve 158 operative. When rendered operative, the check valve 158 serves to lock the knee joint 34 against further flexion, as hereinabove explained.

When employing the adjustable toe control unit 292 described, the position of the toe rod 302 corresponding to the point of inception of operation of the hydraulic brake unit 110 may be adjusted during use. In practice, it is found convenient to make this adjustment to suit the gait of the user and, in particular, to make the adjustment in accordance with the user's walking speed and also in accordance with the slope of the terrain over which the user is walking.

VI. Adjustment of knee joint flexion

In Figs. 17 to 20 inclusive, there are illustrated parts of a mechanism for permitting the knee joint to flex gradually at an adjustably controlled rate. The mechanism for controlling the rate of flexion of the knee joint 34 is similar to that previously described in connection with the artificial leg of Fig. 11, but includes an adjustable throttle valve 370 which is connected in a second passageway 372 which communicates with the spaces 148 and 150 on opposite sides of the knee brake piston 122, and also includes a linkage 374 which is controlled from an adjusting device 376 mounted on the upper leg member 32.

The second passageway 372 is formed in part by a bore passing through a boss 378 which extends laterally from the body 160 of the check valve 158 and communicating with the lower portion of the check valve chamber 162 beneath the valve seat 164. The passageway 372 continues through a transverse throttle valve body 380 which is secured to the boss 378 by means of an apertured screw 382. A tubular member 384 which communicates, at its lower end, with the chamber 386 of the throttle valve body 380 rises upward to a cap member or top plate 388 through which it communicates with the upper portion of the check valve chamber 162 above the check valve seat 164.

In this case, it is to be noted that the upper plug 180 attached to the upper end of the check valve body 160 is provided with a vertical

through-bore 390 which forms part of the second passageway and which communicates with the expansion chamber 392 of an accumulator 394 which is mounted at the upper end of the check valve assembly 158.

A nipple 396 extending downwardly from the accumulator body passes through the top plate 388 and threadably engages the plug 180 to hold the top plate firmly in place. The nipple 396 is provided with a lateral passage 398 which intersects its through-bore 390, and forms part of the second passageway 372. A follower piston 400 is urged downwardly against the force of liquid in the accumulator chamber 392 by means of a compression spring 402 arranged between the piston and a vented cap 404. The accumulator 394 serves to accommodate the expansion and contraction of fluid contained in the brake unit 110 as a result of temperature changes and for volumetric changes therein resulting from movement of the check valve head 169.

The throttle valve 370 is provided with a valve seat 406 at the inner end of the valve chamber 386. A valve head 408 on the inner end of a piston 410 works back and forth within the chamber 386 between a position engaging the valve seat 406 and a retracted position by virtue of the rotation of a threaded stem 412 passing through a threaded bore 413 in a cap piece 414 attached to the outer end of the throttle valve body 380. With this arrangement, when the check valve 158 is operative, the knee joint 34 is locked against flexion as long as the throttle valve 370 remains closed, but as the throttle valve is opened, flexion of the knee joint is permitted at a rate corresponding to the degree of opening of the throttle valve.

In practice, the linkage 374 for controlling the throttle valve 370 also includes an arrangement for rendering the check valve 158 operative independently of actuation of the toe control unit or the heel control unit, so that upon subsequent opening of the throttle valve 370 the desired rate of flexion of the knee joint 34 is obtained. To this end a movable arm 416, 45 having its free end 418 located between the check valve rod 174 and the slave actuator rod 284, is pivotally attached by means of a screw 419 to a bracket 420 which extends forwardly from the slave cylinder body 282. In addition, a slide plate 422 is provided which has a main portion 424 provided with a short vertical slot 426 engaging a pin 428 extending laterally from the movable arm 416. The slide plate 422 also has an outwardly offset portion 430 having another short vertical slot 432 which rides on the boss 378 between two spacers 434 and 435.

The inner end of a divided lever 438 is pivotally attached to the upper end of the slide plate 422 and the outer end thereof engages a slot 440 in the end of a crank 442 which is firmly clamped to the outer end of the throttle valve stem 412. An intermediate point of the lever 438 is attached by means of a tension spring 446 to the end of a first transverse extension arm 444, which extends forwardly of the slide plate 422.

A main link 448 which is piloted by a slot in the top plate 388 is pivotally attached between the branches 450 of the lever 438 and is urged by the spring 446 against the shoulder 452 of a second extension arm 454 which extends forwardly from the slide plate 422. The slide plate 422 is raised and lowered vertically by means of a stiff wire 456 which extends through a

housing 458, which passes through the hole 324 in the lower leg member 30 (see Fig. 11) to the adjusting device 376. The lower and upper ends of the housing 458 respectively are firmly secured to the upper and lower limb members by means of suitable clamps 460 and 462.

The adjusting device 376 which is used for operating the linkage 374 includes a terminal arm 464 attached to the uppermost end of the wire 456 and guided vertically in suitable guides 466 formed in a plate 468 attached to the upper leg member 32. The terminal arm 464 is raised and lowered by means of rollers 470 pivoted thereon, which rollers engage the cam surface of a snail cam 472 rotated by means of an adjusting knob 474 which may be adjustably set by a ball and spring detent, as previously described. It is to be noted that the rollers 470 are mounted above the snail cam 472 and are held firmly against the cam surface by the tension applied to the wire 456 by the coil spring 446. The shaft 476 joining the cam 472 and the knob 474 extends through a vertical slot 478 in the terminal arm 464, and the cam 472 is preferably formed of two similar parts which engage rollers 470 on opposite sides of the terminal arm.

In the normal course of walking with an artificial leg including this system, the throttle valve 370 is held closed by the coil spring 446; and the slide plate 422 is held in its lowermost position by the springs 177 and 178, which float the valve 169 (see Fig. 7) and the weights of the various parts of the linkage 374. During the use of the artificial leg, the actuator rod 284 is raised and lowered in response to predetermined action of the artificial foot, as previously described. As the actuator rod 284 is raised and lowered, it moves the check valve rod 174 up and down through the intermediary action of the outer end 418 of the movable arm 416. Such movement of the arm 416 is not restricted materially by virtue of the fact that the pin 428 is free to move between suitable limits in the lower slot 426 in the slide plate 422. Thus, during the normal operation of walking, the hydraulic brake unit of this artificial leg operates substantially identically with those hereinabove described.

If at any time it is desired to flex the knee while the check valve 158 is in its operative condition by virtue of operation by the slave device 280, the throttle valve may be opened to any desired degree by turning the knob 474 in the adjusting device 376. As this knob is turned, the snail cam 472 rotates, raising the terminal arm 464 a corresponding amount and thus raising the main link 448. As the main link 448 is raised, the lever 438 and the slide plate 422 are carried upward until the lower end of the upper slot 432 engages the boss 378. At that point, further upward movement of the slide plate 422 is discontinued and further raising of the main link 448 causes the lever 438 to rotate on its pivot against the force of the coil spring 446. During this pivotal movement of the lever 438, the outer end thereof turns the crank 442 and thus withdraws the throttle valve head 408 from its seat 406. When the throttle valve 370 is thus opened, assuming the check valve 158 is still operative, fluid passes therethrough from the space 150 beneath the brake piston 122 to the space 148 above the brake piston, permitting the knee joint 34 to flex. The rate at which the knee joint flexes depends on the hydraulic resistance in the sec-

ond passageway, as determined by the degree of opening of the throttle valve 370. Upon returning the control knob 474 to its home position, flexion of the knee joint 34 is discontinued, provided, of course, that the check valve 158 remains operative. During any of this action, it is, of course, possible for the user of the artificial leg to straighten the knee joint by applying the proper force to the artificial leg.

If for any reason it is desired to flex the knee joint at some predetermined rate, even though the check valve is not already in an operative condition as a result of action of either the toe control unit or the heel control unit, the control knob 474 of the adjusting device 376 is manipulated as before. But, in this case, as slide plate 422 is raised, it turns the movable arm 416, forcing the check valve rod 174 upward and rendering the check valve operative before the lever 438 is turned to open the throttle valve 370. In this operation, the closing of the check valve 158 first locks the knee joint 34 and then the check valve is bypassed by the opening of the throttle valve 370. The degree of opening of the throttle valve determines the rate of knee joint flexion.

VII. Mechanical adjustment of toe control unit

In Figs. 20 to 24 inclusive, there are illustrated parts of an artificial leg which include a mechanical arrangement for adjusting the point of inception of the toe control unit. While this arrangement may be adapted directly to the artificial leg illustrated in Fig. 11, it is described herein as applied to such an artificial leg modified by the incorporation of the adjusting mechanism just described. The foot member 36 of this artificial leg employs a ball joint 44 comprising two hinged plates 490 and 492 which are respectively bolted to the toe section 42 and the main foot portion 40. A torsion spring 494 enclosing the hinge shaft 496, which hinges the two plates 490 and 492, normally urges them into alignment and resists flexion of the ball joint 44.

The toe control unit 500 of this artificial foot is of similar construction to that previously described in Fig. 12. However, in this case the master cylinder 502 is mounted in sliding engagement with a guide frame 504 which is firmly bolted to the rear ball joint plate 492. This master cylinder 502 is urged into a forward position by a compression spring 506 arranged between a guide flange 508 formed in the cylinder and the rear-end-plate 510 of the guide frame 504. A pair of stub rods 512 extending laterally from the master cylinder 502 ride in slots 514 in the side walls 516 of the guide frame 504. The free ends of the two laterally spaced arms 518 of a yoke member are pivotally attached to the stub rods 512 on opposite sides of the guide frame 504.

The cross arm 520 of the yoke member is attached to a stiff wire 522 which leads to the adjusting device 376 mounted on the upper limb member and which serves as a control line. The wire 522 is enclosed in a housing 524 which is secured to the main foot section 40 by means of a fitting 526 and is secured to the upper limb member by a clamp 528 attached to a side plate 530 in the adjusting device 376. A compression spring 532, arranged between the yoke cross arm 520 and the fitting 526, aids in forcing the master cylinder 502 into its forward position.

The master cylinder 502 is drawn rearwardly

in the guide frame 504 by raising a lever 534 pivoted on the side plate 530 and attached to the uppermost end of the wire 522. A knurled knob 536 at the outermost end of a screw 538 passing through an arcuate slot 540 in the side plate 530 and into a threaded bore at the outermost end of the lever 534 is used for locking the lever 534 in any desired position on the side plate. A limit stop screw 542, having a knurled head 544, may be adjustably positioned in the slot 540 at any desired position to limit the upward movement of the lever 534. By raising and lowering the lever 534, the master cylinder 502 is moved backward and forward in the guide frame 504 and may be locked at any desired position therein to establish the point of inception of operation of the toe control unit 500.

A toe rod 546 extending through the forward end of the master cylinder 502 is forced forwardly therein by a compression spring 548 which pushes on a piston 550 attached to the toe rod 546 and slidably arranged in the cylinder. A stub shaft 552 extending rearwardly of the piston 550 serves to limit the rearward movement of the piston in the master cylinder 502. A cross slot 554 in the end of the shaft 552 provides communication between the cylinder chamber 556 and the passage 558 in the tailpiece 560 which communicates with the conduit branch 290. To reduce wear on the toe rod, the control element mounted on the toe section 42 comprises an anti-friction roller 562 which rotates on a shaft 564 between two arms 566 extending upwardly from the forward ball joint plate 490.

The operation of the toe control unit 500 is substantially the same as that previously described in connection with Figs. 11 and 12, the main difference being in the substitution of a mechanical arrangement for a hydraulic arrangement for adjusting the point of inception of operation of the control unit. It is to be noted, however, in this case the springs 506, 532, and 548 force master cylinder 502 into its most forward position corresponding to minimum ball joint flexion required for actuation, in the event that part of the adjusting mechanism such as the wire should be broken.

VIII. Electrically controlled knee brake

In Figs. 25 to 28 inclusive there is illustrated an electrically controlled artificial leg employing the principles of my invention. In this case, the slave unit 570, which is mounted on the hydraulic brake unit 110, comprises a solenoid 572 which forces the actuator rod 574 upward to render the check valve 158 operative only when the solenoid is electrically energized.

The battery 592 for energizing the solenoid 572 is preferably mounted in a pocket 594 which is attached to the upper leg member 32. The solenoid 572 is energized by the closure of either of two parallel-connected microswitches 596 and 598 respectively included in a toe control unit 600 and a heel control unit 602. Both microswitches 596 and 598 are normally in open position and are closed to energize the solenoid 572 only when the ball joint flexion or the heel pressure exceeds a corresponding predetermined amount.

The adjustment of the point of inception of operation of the control unit 600 is accomplished by means of a toe bumper 604 carried at the outer end of a sleeve 606 and normally urged rearwardly by a compression spring 608 arranged between the toe bumper 604 and the

inner end of an adjusting screw 610 which carries pins 612 which project outwardly in longitudinal slots 614 in the sleeve. The adjusting screw 610 passes through a threaded block 616 inserted into a recess in the top of the toe section 42 and is employed to adjust the position of the toe bumper 604 thereon. The toe bumper 604 moves along a line which passes radially through the contact closing button 618 mounted on the forward side of the microswitch 598. It is to be noted that the compression spring 608 serves to compensate for excess flection of the ball joint 44 once the microswitch 598 is closed.

The heel control unit 602 includes a push rod 620 which is guided by a collar 621 in a vertical bore 622 in the heel portion 92 of the main foot section 40. The push rod 620 is normally urged into its downward position by means of a compression spring 624 arranged between a head 626 attached to its lower end and an inwardly extending flange 628 formed in the upper end of a tube 630 suitably secured within the bore 622. The flange 628 of the tube 630 also serves as a stop to limit the downward movement of the push rod 620 by engaging the collar 621. In response to heel pressure, the push rod 620 is forced upwardly into engagement with a button 632 of the heel microswitch 598. The adjustment of the point of inception of operation of this microswitch 598 is accomplished by means of an adjusting screw 634 which works against a rearwardly extending leaf spring 636 which supports the microswitch 598 on the main foot section 40.

The solenoid 572 is mounted in a recess 576 in a cup-shaped member 578 which registers the actuator rod 574 with the valve rod 174, as hereinabove explained in connection with Fig. 7. A sleeve 579 composed of non-magnetic material is arranged with the solenoid and a screw cap 583 serves to hold the solenoid and sleeve in place.

A cylindrical core 582 composed of magnetic material is secured to the lowermost end of the actuator rod 574 and the actuator rod is piloted by a bore 584 in the cap and a bore 586 in the bottom wall forming the recess 576. A compression spring 588 arranged between the cap 583 and the core 582 serves to urge the actuator rod 574 downward away from the check valve 153. With this arrangement, when the solenoid 572 is energized, the magnetic core 582 is drawn upwardly therein against the force of the spring 588, causing the actuator rod 574 to engage the valve rod 174. By applying sufficient current to the solenoid the check valve is rendered operative.

IX. Summary

From the foregoing description of my invention, it is apparent that I have provided a knee lock mechanism for artificial legs which offers many advantages over those available heretofore. Looked at broadly, this knee lock mechanism includes a knee brake unit which is actuated in response either to toe joint flection or to heel pressure. While the particular knee brake unit which I have illustrated is of the hydraulic type, it is to be understood that other types of brake units may be employed, even brake units which operate on mechanical or electrical principles. Furthermore, it is to be understood that the knee brake mechanism may under some circumstances be actuated in other ways without departing from the principles underlying my invention.

While the particular means which I have illustrated to actuate the knee brake unit includes toe control and heel control units of specific mechanical, hydraulic, and electrical forms, it is also to be understood that other forms of control units may be readily devised by those skilled in the art without departing from the principles underlying my invention. In a like manner it is to be understood that many changes may be made in other features of my invention which have been described, such as the devices which are employed for adjusting the toe control and heel control units and the device for adjustably flexing the knee joint, without departing from the principles of my invention.

Accordingly, since many modifications and changes can be made in the construction and arrangement of the parts of my invention by those skilled in the art without departing from the true spirit and scope of my invention, it is to be understood that my invention is not to be limited to the specific forms illustrated and described but is to be construed broadly in the light of the appended claims.

I claim as my invention:

1. An artificial leg comprising upper and lower leg members pivotally attached by a knee joint, a braking device comprising a pair of cooperating brake members respectively connected to said upper and lower leg members, said brake members being adapted upon operation to resist flection of said knee joint, an articulated foot member having a main section pivotally attached to the lower leg member and a toe section pivotally attached to said main section by a ball joint, first and second cylinders mounted respectively at the forward and rear ends of said main foot section, common hydraulic conduit means communicating with the interiors of said cylinders, means controlled by movement of fluid in said hydraulic conduit means for operating said braking device, a first piston slideably arranged in said first cylinder and adapted to slide therein upon flection of said ball joint beyond a predetermined amount whereby flection of said knee joint is resisted, and a second piston slideably arranged in said second cylinder adapted to slide therein upon application of pressure exceeding a predetermined amount to the heel portion of said main foot section whereby flection of said knee joint is resisted.

2. An artificial leg comprising upper and lower leg members pivotally attached by a knee joint, a braking device comprising a hydraulic cylinder and a piston working therein connected between said upper and lower leg members, a check valve mechanism arranged in a passageway interconnecting spaces in said cylinder on opposite sides of said piston, said check valve mechanism being operative to block the flow of fluid in one direction in said passageway whereby flection of said knee joint is prevented without interfering with extension of said knee joint, an articulated foot member having a main section pivotally attached to the lower leg member and a toe section pivotally attached to said main section by a ball joint, a first control device adapted for actuation upon flection of said ball joint beyond a predetermined amount, a second control device adapted for actuation upon application of pressure exceeding a predetermined amount to the heel portion of said main foot section, and common means controlled by actuation of either of said control devices for rendering said check valve mechanism operative whereby said knee joint is locked.

against flection upon occurrence of such ball joint flection or such heel pressure.

3. An artificial leg comprising upper and lower leg members pivotally attached by a knee joint, a braking device comprising a pair of cooperating brake members respectively connected to said upper and lower leg members, said braking device being adapted upon operation to resist flection of said knee joint, an articulated foot member having a main section pivotally attached to said lower leg member and a toe section pivotally attached to said main section by a ball joint, actuating means located adjacent the ball joint and controlled by flection of said ball joint beyond a predetermined amount for operating said braking device whereby flection of said knee joint is resisted, said actuating means comprises an actuating member mounted on the main foot section, said actuating member being arranged to contact part of said toe section upon flection of said ball joint beyond a predetermined amount whereby said braking device is operated, said artificial leg also comprising a carriage member movably mounted on said main foot section and carrying said actuating member, a control line connected at its lower end to said carriage member and having its upper end mounted upon the upper leg member, and an adjusting device at said upper end for adjustably transmitting a force to said carriage member through said control line to adjust the position of said actuating member on said main foot section whereby the degree of ball joint flection corresponding to inception of operation of said braking device is varied.

4. An artificial leg as defined in claim 3 wherein said control line is in the form of a stiff wire arranged in a flexible tubular housing which is led upward from said foot member through the lower leg member to a position on the outside of said upper leg member, the lower end of said tubular housing being firmly attached at the lower end of said main foot section and the upper end thereof being firmly attached to said upper leg portion, and said adjusting device including means for moving said stiff wire lengthwise in said tubular housing for effecting the desired movement of the carriage member.

5. An artificial leg as defined in claim 4 comprising a spring arranged to force said actuating member toward a position in which inception of brake operation occurs at a relatively low degree of ball joint flection.

6. An artificial leg comprising upper and lower leg members pivotally attached by a knee joint, a braking device comprising a pair of cooperating brake members respectively connected to said upper and lower leg members, said braking device being adapted upon operation to resist flection of said knee joint, an articulated foot member having a main section pivotally attached to the lower leg member and a toe section pivotally attached to said main section by a ball joint, a primary cylinder mounted on said main foot portion, a secondary cylinder mounted as a piston within said primary cylinder, adjusting means including a first hydraulic line communicating with the interior of said primary cylinder for adjusting the position of said secondary cylinder relative to said main foot section, a piston slideably arranged within said secondary cylinder, an actuating member connected to said piston and arranged to be moved upon ball joint flection beyond a predetermined amount determined by the position of said secondary cylinder

relative to said main foot section, and means including a second hydraulic line communicating with the interior of said secondary cylinder for operating said brake device whereby flection of the knee joint is resisted when the ball joint is flexed more than said predetermined amount.

7. An artificial leg as defined in claim 6 wherein in the upper end of said first hydraulic line terminates adjacent the hip position of said upper leg member, said artificial leg also comprising a plunger slideably arranged in the upper end of said hydraulic line, and means for manually adjusting the position of said plunger in said hydraulic line for effecting the desired adjustment of the position of said secondary cylinder.

8. An artificial leg comprising upper and lower leg members pivotally attached by a knee joint, a braking device comprising a pair of cooperating brake members connected to said upper and lower leg members respectively, said brake members being adapted upon operation to resist flection of said knee joint, a foot member pivotally attached to the lower leg member, a push rod passing upwardly through the point of pivoting of said foot member on said lower leg member, said push rod terminating adjacent the ankle and means controlled by upward pressure on the heel portion of said foot member for urging said push rod upwardly, and means including a second rod engaging said push rod adjacent the ankle controlled by upward movement of said push rod for operating said braking device whereby flection of said knee joint is resisted.

9. An artificial leg comprising upper and lower leg members pivotally attached by a knee joint, a braking device comprising a pair of cooperating brake members connected to said upper and lower leg members respectively, said brake members being adapted upon operation to resist flection of said knee joint and upon release to permit flection, a foot member pivotally attached to the lower leg member by an ankle joint, a movable foot portion located in the lower part of said main foot member and movable relative to said main foot member, means resiliently forcing said foot portion downward relative to said main foot member, a pilot element mounted on said foot member and rotatable therewith, a mechanical element extending through said pilot element from said main foot member to said lower leg member through the axis of said ankle joint and movable upwardly and downwardly therein and means connected to said mechanical element adjacent the ankle for operating and releasing said braking members, means controlled by upward movement of said foot portion relative to said main foot member for moving said mechanical element upwardly through said pilot element, whereby said flection of said knee joint is resisted in accordance with said relative movement of said foot portion independently of the angular position of said main foot member relative to said lower leg member.

10. In an artificial leg, the combination which comprises upper and lower leg members pivotally attached by a knee joint, a braking device comprising a hydraulic cylinder and a piston working therein connected between said upper and lower leg members, a check valve arranged in a first passageway interconnecting spaces in said cylinder on opposite sides of said piston, said check valve being operative to block the flow of fluid in one direction in said first passageway whereby flection of said knee joint is prevented without interfering with extension of said knee joint, a

throttle valve arranged in a second passageway interconnecting the spaces in said cylinder on opposite sides of said piston, and control means including an adjusting member mounted above said knee joint for adjustably opening said throttle valve while said artificial leg is in use whereby fluid is permitted to flow past said check valve at a variably controlled rate while said check valve is operative so as to control the rate of flexion of said knee joint.

11. An artificial leg as defined in claim 10 wherein said adjusting member comprises a pivoted handle at the hip position of the upper leg member.

12. An artificial leg comprising upper and lower leg members pivotally attached by a knee joint, a braking device comprising a hydraulic cylinder and a piston working therein connected between said upper and lower leg members, a check valve arranged in a first passageway interconnecting spaces in said cylinder on opposite sides of said piston, said check valve being adapted to be rendered operative to block the flow of fluid in one direction in said first passageway whereby flexion of said knee joint may be prevented without interfering with extension of said knee joint, means controlled by predetermined movement of part of said artificial leg for rendering said check valve operative whereby said knee joint is locked against flexion, a throttle valve arranged in a second passageway interconnecting the spaces in said cylinder on opposite sides of said piston, and control means including an adjusting member mounted above said knee joint for adjustably opening said throttle valve whereby fluid is permitted to flow past said check valve at a variably controlled rate while said check valve is operative so as to control the rate of flexion of said knee joint.

13. An artificial leg comprising upper and lower leg members pivotally attached by a knee joint, a braking device comprising a hydraulic cylinder and a piston working therein connected between said upper and lower leg members, a check valve mechanism arranged in a first passageway interconnecting spaces in said cylinder on opposite sides of said piston, said check valve mechanism being adapted to be rendered operative to block the flow of fluid in one direction in said first passageway whereby flexion of said knee joint may be prevented without interfering with extension of said knee joint, a throttle valve arranged in a second passageway interconnecting the spaces in said cylinder on opposite sides of said piston whereby fluid may be flowed past said check valve at a variably controlled rate while said check valve is operative, and common control means for rendering said check valve operative and for then adjusting the opening of said throttle valve whereby the rate of flexion of said knee joint is varied.

14. An artificial leg comprising upper and lower leg members pivotally attached by a knee joint, a braking device comprising a hydraulic cylinder and a piston working therein connected between said upper and lower leg members, a check valve arranged in a first passageway interconnecting spaces in said cylinder on opposite sides of said piston, said check valve being operative to block the flow of fluid in one direction in said first passageway whereby flexion of said knee joint may be prevented without interfering with extension of said knee joint, a throttle valve arranged in a second passageway interconnecting the spaces in said cylinder on opposite sides of said

piston whereby fluid may be flowed past said check valve at a controlled rate while said check valve is operative, a control handle having an inoperative position and a range of operative positions, common means controlled by predetermined movement of a part of said artificial leg and by movement of said control handle from said inoperative position into said range of operative positions for rendering said check valve operative whereby said knee joint is locked against flexion, and means controlled by further movement of said control handle in said range of operative positions for adjusting the opening of said throttle valve whereby the rate of flexion of said knee joint is varied.

15. An artificial leg comprising upper and lower leg members pivotally attached by a knee joint, a cylinder body and a piston working therein connected between said upper and lower leg members, a check valve housing mounted on said cylinder body and provided with a passageway interconnecting spaces in said cylinder body on opposite sides of said piston and also provided with a valve seat in said passageway, a check valve head guided in said passageway, a check valve shaft extending through said check valve housing, means operatively associated with said valve head for normally maintaining said check valve head in a position withdrawn from said valve seat, and means controlled by movement of a part of said artificial leg for moving said valve shaft to force said valve head against said valve seat whereby the flow of fluid is blocked in one direction in said passageway thereby locking said knee joint against flexion.

16. An artificial leg as defined in claim 15, comprising spring means arranged between said valve shaft and said valve head for floating said valve head in said passageway whereby the flow of fluid in a direction opposite to said one direction is facilitated to permit knee joint flexion.

17. An artificial leg comprising upper and lower leg members pivotally attached by a knee joint, a cylinder body and a piston working therein connected between said upper and lower leg members, a check valve housing mounted on said cylinder body and provided with a passageway interconnecting spaces in said cylinder body on opposite sides of said piston and also provided with a valve seat in said passageway, a check valve head guided in said passageway, a check valve rod extending through said check valve housing, means for normally urging said check valve head into a position withdrawn from said valve seat, actuator means mounted on said cylinder body and operatively associated with said valve rod for moving said valve head into and out of engagement with said valve seat, and means controlled by a predetermined movement of a part of said artificial leg for operating said actuator means to force said valve head against said valve seat, whereby the flow of fluid is blocked in one direction in said passageway thereby locking said knee joint against flexion.

18. An artificial leg comprising upper and lower leg members pivotally attached by a knee joint, a brake cylinder body and a brake piston working therein connected between said upper and lower leg members, a check valve housing mounted on said brake cylinder body and provided with a passageway interconnecting spaces in said brake cylinder body on opposite sides of said piston and also provided with a valve seat in said passageway, a check valve head guided in said passageway, a check valve rod extending

through said check valve housing, means for normally urging said check valve head into a position withdrawn from said valve seat, a slave cylinder mounted on said brake cylinder body, a slave piston working in said slave cylinder, an actuator rod connected to said slave piston and operatively associated with said valve rod for moving said valve head into and out of engagement with said valve seat, a master cylinder mounted on said artificial leg and communicating with said slave cylinder by means of a hydraulic line, a master piston working in said master cylinder and operative to displace fluid therein in response to predetermined movement of a part of said artificial leg whereby said actuator rod is moved to force said valve head against said valve seat whereby the flow of fluid is blocked in one direction in said passageway thereby locking said knee joint against flection.

19. An artificial leg comprising upper and lower leg members pivotally attached by a knee joint, a cylinder body and a piston working therein connected between said upper and lower leg members, a check valve housing mounted on said cylinder body and provided with a first passageway interconnecting spaces in said cylinder body on opposite sides of said piston and also provided with a valve seat in said passageway, a check valve head guided in said passageway, a check valve shaft extending through said check valve housing, means for normally urging said check valve head into a position withdrawn from said valve seat, an actuator rod aligned with said valve stem, a throttle valve arranged in a second passageway interconnecting the spaces in said cylinder on opposite sides of said piston, a movable arm arranged between said actuator rod and said valve stem, means controlled by predetermined movement of a part of said artificial leg for forcing said actuator rod against said floating arm and the floating arm in turn against said valve shaft for forcing said valve head against said valve seat, means for forcing said movable arm against said valve shaft to force said valve head against said valve seat independently of said predetermined movement, said check valve being operative when said valve head is seated to block the flow of fluid in one direction in said first passageway thereby locking said knee joint against flection, and means for adjustably opening said throttle valve while said check valve is operative whereby fluid flows past said check valve at a controlled rate to control the rate of flection of said knee joint.

20. An artificial leg comprising upper and lower leg members pivotally attached by a knee joint, a cylinder body and a piston working therein connected between said upper and lower leg members, a check valve housing mounted on said cylinder body and provided with a first passageway interconnecting spaces in said cylinder body on opposite sides of said piston and also provided with a valve seat intermediate the ends of said passageway, a check valve head guided in said passageway, a check valve shaft extending through said check valve housing, means for normally urging said check valve head into a position withdrawn from said valve seat, a movable arm operatively associated with said valve shaft, a throttle valve arranged in a second passageway interconnecting the spaces in said cylinder on opposite sides of said piston, control means for moving said arm relative to said valve shaft whereby said valve head is forced against said valve seat thereby blocking the flow of fluid in

one direction in said first passageway and then adjustably opening said throttle valve whereby fluid flows in an opposite direction in said second passageway at a controlled rate thereby controlling the rate of flection of said knee joint.

21. In a locking device for an artificial limb comprising two members pivotally attached at a joint, a valve body adapted for pivotal attachment to one of said limb members, said valve body comprising a working cylinder, a working piston slideably arranged in said working cylinder and guided therein by a rod passing through said valve body, said rod being adapted for pivotal attachment to the other limb member, a passageway arranged in said valve body and communicating with said working cylinder on opposite sides of said working piston, a valve seat arranged in said passageway, a check valve head movable in said passageway between an operative position in engagement with said valve seat and a withdrawn position out of engagement with said valve seat, a valve shaft projecting through said valve body and operatively associated with said valve head, spring means normally urging said valve head into said withdrawn position and for urging said valve shaft into a corresponding position, and means responsive to predetermined movement of said artificial limb for moving said valve shaft against the force of said spring means to force said valve head into operative position.

22. In a locking device for an artificial limb comprising two members pivotally attached at a joint, a valve body adapted for pivotal attachment to one of said limb members, said valve body comprising a working cylinder, a working piston slideably arranged in said working cylinder and guided therein by a rod passing through said valve body, said rod being adapted for pivotal attachment to the other limb member, a passageway arranged in said valve body and communicating with said working cylinder on opposite sides of said working piston, a valve seat arranged in said passageway, a check valve head carried by a valve piece which is slideably arranged in a guide bore passing through said valve body, a valve shaft slideably arranged in said guide bore, a first spring passing through said valve seat arranged between said valve head and said valve body, a second spring arranged between said valve piece and said valve shaft, said springs cooperating to urge said valve head into said withdrawn position and said valve shaft into a corresponding position, and means responsive to predetermined movement of said artificial limb for moving said valve shaft against the forces of said springs to force said valve head into operative position.

23. An artificial foot comprising a main foot section adapted for support on an artificial leg, a toe section pivotally attached to said main foot section by a ball joint, a control cylinder mounted on said main foot section and adapted for connection to a control conduit, and a piston slideably arranged in said cylinder and carrying a piston rod adapted to be engaged by said toe section upon flection of said ball joint.

24. An artificial foot as defined in claim 23, comprising a guide mounted on said main foot portion, said control cylinder being slideably arranged on said guide, and a spring urging said cylinder into a forward position on said guide.

25. An artificial foot as defined in claim 23, comprising a second cylinder operatively enclosing said control cylinder whereby said control

cylinder acts as a piston therein, said second cylinder including a connection for establishing communication of the working space therein with a conduit.

26. An artificial foot as defined in claim 25, including a spring for urging said control cylinder in a direction to reduce the volume of said working space. 5

27. An artificial foot as defined in claim 23, comprising an antifriction roller mounted on said toe section for operatively engaging said piston rod during flexion of said ball joint. 10
